UNITED STATES PATENT OFFICE

118,020

DESIGN FOR A SHOE

Arthur E. Pfeiffer, Worcester, Mass.

Application July 28, 1939, Serial No. 86,294

Term of patent 3½ years

To all whom it may concern:

Be it known that I, Arthur E. Pfeiffer, a citizen of the United States, residing at Worcester, in the county of Worcester and State of Massachusetts, have invented a new, original, and ornamental Design for a Shoe, of which the following is a specification, reference being had to the accompanying drawing, forming part thereof, wherein—

The single figure of the drawing is a perspective view of a shoe showing my new design.

I claim:

The ornamental design for a shoe, substantially as shown.

ARTHUR E. PFEIFFER.
